US0D1025983S

(12) **United States Design Patent** (10) **Patent No.:** **US D1,025,983 S**
(45) **Date of Patent:** **** May 7, 2024**

(54) **MONITOR**

(71) Applicant: **LG ELECTRONICS INC.**, Seoul (KR)

(72) Inventors: **Sharim Choe**, Seoul (KR); **Daihyung Ryu**, Seoul (KR); **Hyeongyeol Kim**, Seoul (KR)

(73) Assignee: **LG ELECTRONICS INC.**, Seoul (KR)

(**) Term: **15 Years**

(21) Appl. No.: **35/513,182**

(22) Filed: **Jun. 15, 2021**

(80) **Hague Agreement Data**

Int. Filing Date: **Jun. 15, 2021**

Int. Reg. No.: **DM/215093**

Int. Reg. Date: **Jun. 15, 2021**

Int. Reg. Pub. Date: **Dec. 17, 2021**

(30) **Foreign Application Priority Data**

Jan. 5, 2021 (KR) 30-2021-0000339

(51) **LOC (14) Cl.** **14-02**

(52) **U.S. Cl.**

USPC **D14/371**
